Primary Examiner — Philip S. Hyder*Assistant Examiner* — John T Applewhite(57) **CLAIM**

The ornamental design for a LED spot light for camera, as shown and described.

DESCRIPTION

FIG. 1 is a perspective view of a LED spot light for camera in accordance with the present design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view of the LED spot light for camera.

The broken lines shown are for illustration purposes only and form no part of the claimed design.
